UNITED STATES PATENT OFFICE.

JOSEPH B. SMITH, OF SALT LAKE CITY, UTAH.

BROODER STOVE.

Application filed October 1, 1926. Serial No. 138,994.

The invention relates to improvements in heaters designed primarily for poultry brooders, and my principal aim is to provide a unique construction and relation of dampers for attaining the desired ends, provision being made whereby upon heating of the stove to a predetermined extent, the draught thereto will be cut off, one damper plate will be substantially closed across the smoke outlet, another damper plate will be opened to admit air into the smoke outlet, and openings in the first named damper plate will be exposed, so that some of the air entering said smoke passage, may descend to cool the fire, while the remaining air entering the smoke passage, may ascend to produce effective ventilation of the brooder stove and house.

With the foregoing and minor objects in view, the invention resides in the novel subject matter hereinafter described and claimed, the description being supplemented by the accompanying drawings.

Figures 1 and 2 are side elevations partly broken away and in section, looking in different directions, the hover being omitted from these views.

Fig. 3 is a vertical sectional view taken substantially on line 3—3 of Fig. 1;

Fig. 4 is a horizontal section on line 4—4 of Fig. 2;

Fig. 5 is a small side elevation of the stove with the hover connected therewith, the latter being shown in section.

In the drawings above briefly described, 6 designates the base of the stove, supporting the ashpit 7 from which the substantially cylindrical body 8 rises, said body having a fuel inlet door 9 at any suitable point, preferably near its upper end and being provided with an appropriate grate 10. Any desired provision may of course be made for shaking this grate. 11 designates a door for removing ashes from the ashpit 7, and it will be understood that the bottom of this ashpit is spaced above the brooder floor by the base 6, so that there is no danger of fire. Moreover, this base is formed with openings 12 which permit passage of air under the ashpit, keeping the same comparatively cool.

The stove is provided with two down-draught passages 13 whose lower ends open under the grate 10. The upper ends of these passages are controlled by two dampers 14 carried by the outer end of a pair of

levers 15, these levers being suitably mounted at 16 upon the upper end of the stove. An operating rod 17 is appropriately connected with the inner ends of the levers 15 and is automatically operated by means hereinafter described, to control the draught to the fire. 18 designates a preferably rectangular smoke outlet member which is appropriately mounted upon the stove body 8, the upper end of this member 18 being preferably provided with a collar or the like to connect with an ordinary smoke pipe 20, leading to any remote point outside of the brooder. The member 18 is formed with an air inlet opening 21, and within this member, near the opening, are two damper plates 22 and 23. The plate 22 is imperforate and is pivoted on a horizontal axis 24 about one inch below the lower edge of the opening 21, said plate when in the dotted line position of Fig. 3 serving to close the opening 21 against entrance of air. The reason I pivot this damper plate 22 below the lower edge of opening 21 is to form a pocket to catch any sparks that may come down the chimney, thus preventing danger of fire.

An arm 25 is secured to and projects outwardly from the damper plate 22, said arm being pivoted to the upper end of a rod 26 which is operatively associated at its lower end with an appropriate thermostat 27 suitably secured to the stove. If desired, any suitable provision (not shown) may be made for extending or retracting the length of the rod 26 to control the automatic operation of the damper plate 22, under the influence of the thermostat 27.

A second arm 28 projects outwardly from the damper plate 22 and is pivoted to the upper end of the rod 17. By this provision, when the thermostat 27 expands under predetermined heat and moves the damper plate 22 inwardly to admit air through the opening 21, the arm 28 pulls upwardly upon the rod 17, thus actuating the two levers 15 to close the dampers 14, thereby cutting off the draught to the fire. Similarly, when the thermostat contracts and the damper plate 22 is consequently moved to or toward the dotted line position of Fig. 3, the arm 28 and rod 17 cause such movement of the levers 15, as to again open the draught controlling dampers 14.

The damper plate 23 hangs vertically in the dotted line position of Fig. 3, when the plate 22 is closed, said plate 23 being then

positioned at the inner side of said plate 22. The pivotal mounting 29 of plate 23 is above the upper end of the plate 22 and also above the opening 21, and it will be observed also 5 from Fig. 3 that above said plate 22, the plate 23 is formed with a relatively large opening 30, while it is formed with a smaller opening 31 below the upper end of plate 22.

The movements imparted to the plate 22 10 by the thermostat 27, control the movements of the plate 23, and as said plate 22 is moved inwardly to the full line position of Fig. 3, it swings the plate 23 to an oblique position across the smoke outlet member 18. When 15 this position is reached, both openings 30 and 31 are exposed. Thus, the air entering through the opening 21 may pass through the opening 30 and while some of this air may descend through the opening 31 to cool 20 the fire, the remainder of such air will pass upwardly through the smoke outlet, thus carrying off all foul air from the brooder stove.

An appropriate supporting ledge 32 is provided 25 near the upper end of the body 8 for the purpose of supporting a sheet metal hover 33, said hover declining outwardly from the upper end of the stove to a plane spaced a desired distance above the brooder 30 floor. Under this hover, the stove is provided with an air heating drum 34 which extends around a portion of its circumference, said drum having an inlet 35 at its lower end for fresh air from any desired source. The 35 upper end of the drum 34 however, is open so that the fresh air which enters through the inlet 35 and is warmed in the drum 34, will be discharged under the hover and will consequently be downwardly directed onto 40 the chicks.

Any appropriate mechanical details may be utilized in the manufacture of the heater. For instance, some parts may be made of 45 castings or sheet metal, some parts may be either integral with others or formed separately, sectional construction may be used whenever advantageous, and parts may be secured by riveting, welding, bolting or in any desired manner, such details being left to 50 the manufacturer for selection. Moreover, it may be explained that provision may be made permitting raising and lowering of the hover 33 if desired. Here again, any adequate mechanical provision may be made 55 for the purpose.

Excellent results are obtainable from the

general construction shown and described and such construction may therefore be followed. However, within the scope of the invention as claimed, variations may of course 60 be made.

I claim:

1. In combination with a substantially vertical smoke outlet passage having an air inlet opening in one vertical side; a damper 65 plate pivoted in said passage on a horizontal axis spaced below said opening and in parallel relation with said one side, said damper plate in one position being adapted to close said opening, a second damper plate pivotally hung in said passage upon an axis spaced above said opening and the upper end of the first named damper plate, said second plate contacting with the inner side of said first named plate to be swung by the 75 latter to an oblique position across the passage, said second plate having an opening in its lower end and an opening in its upper end above said air inlet opening, said lower and upper openings being exposed when said second damper plate is in said oblique position, and operating means connected to the first named damper plate.

2. In combination with a smoke outlet passage having an air inlet opening in one side; a damper plate pivoted in said passage on a transverse axis at one side of said opening, said damper plate in one position serving to close said opening, a second damper plate pivotally mounted in said passage upon a transverse axis near the opposite side of the opening, said second damper plate contacting with the inner side of the first named damper plate to be swung by the latter to an oblique position across 95 the passage, said second plate having an opening in its free end and a second opening in its pivoted end, both of these openings being exposed when said second damper plate is in said oblique position, at which time these openings are disposed at opposite sides of the contacting portion of the first named damper plate, both openings of the second damper plate being closed by the first named plate and the aforesaid side of the smoke passage when said plates lie parallel with said side, and operating means connected to said first named damper plate.

In testimony whereof I have hereunto affixed my signature.

JOSEPH B. SMITH.
